Patented Oct. 8, 1918.

Fig. 1.

UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

TYPE-WRITING MACHINE.

1,281,160.

Specification of Letters Patent.

Patented Oct. 8, 1918.

Application filed January 8, 1917. Serial No. 141,092.

To all whom it may concern:

Be it known that I, FREDERICK A. HART, a citizen of the United States, residing in Newark, in the county of Essex and State of New Jersey, have invented certain new and useful Improvements in Type-Writing Machines, of which the following is a specification.

This invention relates to an improvement in typewriting machines, and more especially to means for properly obtaining a differential feed between a work-sheet on the platen and a tally-strip also on the platen beneath the work-sheet. This invention is an improvement on my application No. 870,972, filed November 9, 1914 (Patent No. 1,212,940 of January 16, 1917.)

It is shown in the above-mentioned application how a differential line-feeding movement could be effected between a work-sheet and a tally-strip. The object of this is to have the lines on the work-sheet spaced apart from each other a considerable distance so as to be easily legible, while the tally-strip or record has its lines close together, so as to greatly condense the same.

If the work-sheet be stripped too quickly from the platen, it has a tendency to drag the tally-strip with it. This might result in some cases in the tearing of one or the other work-members, and in other cases in the displacement of the tally-strip, so that when a subsequent work-sheet is placed on the platen, proper spacing or alinement might not be obtained.

According to one feature of the present improvements, the tally-strip may be positively fed by means connected to be driven at the same time the platen is line-spaced. The extent of movement, however, may be different; that is to say, the tally-strip may be spaced considerably less than the work-sheet, so as to have the record on the tally-strip condensed in as small a space as possible. As there would be a tendency for the tally-strip to be dragged along by the platen and the work-sheet because of the greater movement thereof, means is provided for effecting a drag on that end of the tally-strip which has not yet come around to the printing point of the platen. This drag in the present case is made resilient by means of a spring. Even if the tally-strip should be

pulled around a certain amount, it will readjust itself as soon as the extra feeding pull has ceased.

The back-drag on the tally-strip is obtained by the tally-strip itself winding up a spring to a certain tension which tension is limited by a slip clutch arrangement between the tally-strip and the spring, thus giving an adequate but not excessive back-pull on the tally-strip.

In the present instance, the drive or feeding of the tally-strip is obtained by winding the strip on a reel which is positively driven by a pawl-and-ratchet mechanism, distant from the reel and adjacent to the line-space mechanism of the platen. In order to prevent any back lash by the reel unwinding a one-way acting dog is provided at the reel. This also enables the maintenance of the tally-strip in proper position in case the drive to the reel is interrupted, for which provision is made.

Other features and advantages will hereinafter appear.

In the accompanying drawings, Figure 1 is a perspective view of the platen and the various parts enabling a differential drive between the tally-strip and the work-sheet.

Fig. 2 is a detail section showing the manner of attaching the fresh paper or tally-strip roll to the mechanism.

Fig. 3 is a vertical section, looking from left to right, of Fig. 1.

Fig. 4 is a vertical section taken through the device for obtaining a limited retard on the tally-strip.

Fig. 5 is a fragmentary section, showing the manner of attaching the friction clutch hub to the spring shaft.

Fig. 6 is a vertical section from front to rear taken about mid-way of the tally-strip, winding and unwinding mechanism.

Referring more particularly to the separate parts of this invention, 1 indicates the platen which is supported in the usual way by means of a shaft 2 on an inner carriage or platen frame 3. In order to rotate the platen, there is provided a line-space mechanism which includes the ratchet wheel 4 secured to the shaft 2 at the left hand end thereof. The ratchet 4 may be differentially operated, as is common in the Underwood

typewriter, by means of a pawl 5 carried by a slide 6 which is operated by a line-space lever 7.

The platen 1 may be used to support a work-sheet of any desired type, which in the present case is used to coöperate with a tally-strip 8 to obtain a series of individual pieces of work on separate work-sheets and a condensed duplicate of all the pieces of work on the tally-strip. The tally-strip 8 is furnished in the form of a roll of paper 9, whose method of unwinding and feeding around the platen 1 will now be described.

Mounted on the sides of the platen frame 3 there are provided a pair of brackets 10 and 11 which form supports for shafts 12 and 13 extending parallel to the axis of the platen 1. The shaft 13 is detachably mounted on the brackets 10 and 11 in a manner described in my above-mentioned application so that a pair of spool heads 14 and 15, Figs. 1 and 2, may be loosely mounted thereon. Each of these spool heads is provided with a split expanding tube 16, so that it may be wedged within the core 17 of the reel of tally-strip 9. The tubes 16 are provided with suitable barbs 18 so as to firmly bind on the core 17, and thus rotate with the core and the tally-strip 9 as the tally-strip is unwound from the latter. Loosely mounted on each of the tubes 16 there is provided a disk 19 which properly guides the tally-strip as it unwinds on the reel.

In the case of the right hand hub 15 there is also provided a gear 20 which is secured to the hub to rotate with the core 17 as the tally-strip unwinds from the latter. This gear 20 meshes with a gear 21 so as to drive the same. The gear 21 is loosely mounted on a hub 22, Fig. 4. The hub 22 extends up on one side of the gear 21, while a friction disk 23 faces on the opposite side of the gear 21. A spring 24 acting on the disk 23 causes the gear 21 to be clutched to the hub 22 by friction so as to enable the gear 21 to drive the hub 22, unless there is an excessive back drag on the hub 22. The reaction of the spring 24 is taken care of by a washer 25 also mounted on the hub 22 and prevented from movement from off the hub. The hub and openings in the disk 23 and the washer 25 are flat sided so as to prevent relative rotation. The hub 22 is mounted on a shaft 26 so as to rotate therewith, as by having its opening and the shaft 26 flat sided. The shaft 26 extends through collars or bushings 27 and 28 mounted in side plates 29 and 30 of the tally-strip supporting frame. Sleeved on to the collars 27 and 28 there is provided a tubular casing which incloses a spiral spring 32 wound around the shaft 26. One end of the spring 32 is secured to the shaft 26 and the other end is secured against movement by means of a

screw 34 extending through the casing 31 65 and engaging the collar 28.

It will thus be seen that as the tally-strip roll 9 turns with the unwinding of the tally-strip, the gear 20 will drive the gear 21 to wind up the spring 32 until the tension 70 thereon becomes so great that a slipping will take place between the gear 21 and the hub 22 which with the disk 23 forms a slip clutch.

The manner of unwinding the tally-strip will now be explained. The tally-strip 8 75 passes from the roll 9 down in back of the platen to the right of the same and up in front of the platen so as to be exposed to the striking of type-bars 35 at the printing point. The tally-strip 8 is placed nearest 80 the platen 1, next a carbon sheet on top of the tally-strip, and then a work-sheet on top of the carbon. The usual ribbon 36 enables the printing on the work-sheet while the carbon enables the printing on the tally-strip. The free end of the tally-strip is extended up into a slot 37 provided in a tubular reel 38 to rotate between side plates 29 and 30.

The reel 38 is positively driven so as to 90 wind up the tally-strip 8, as the work is written on line by line. To do this, on the left hand end of the reel there is provided a gear 39 which is driven by a gear 40. The gear 40 is connected to be driven by the shaft 95 12 which is provided with a ratchet wheel 42 driven by a pawl 43, the pawl 43 is pivoted on a rocker 44 and held in engagement with the ratchet wheel 42 by means of a spring 45. The rocker 44 is actuated by 100 means of a link 46 connected to the slide 6 so as to be actuated when the line-space lever 7 is operated to rotate the platen 1. That is to say that the platen 1 and the reel 38 have a common drive. The gearing and 105 ratchets however are so designed that the tally-strip will preferably have a drive of considerably less magnitude than that given the work-sheet by the platen. This will give fairly wide line-spacing for the platen 110 and close or condensed line-spacing for the tally-strip.

As the work-sheet and tally-strip are to have a differential movement, it is preferable that the work-sheet be somewhat wider than the tally-strip, so that spring actuated feed and pressure rollers 47 may act on the side edges of the work-sheet and still clear the tally-strip 8 beneath the work-sheet, as shown in Fig. 1. The rollers 47 may be 120 brought into play and released in the usual manner from a finger-piece 48 through the connecting mechanism indicated in general at 49.

In this type of work, the work-sheets are 125 inserted and removed one by one while the tally-strip remains on the machine, offering a continuous surface to accumulate the rec-

ord of the several independent items on the different work-sheets.

It is sometimes desirable to interrupt connections between the reel which winds up the tally-strip and the drive therefor. To do this, the gear 40 is not directly connected to the shaft 12, but is splined on a sleeve 50 which is secured to the shaft 12. The gear 40 is normally held in register with the gear 39 by means of a spring 51, but can be shifted sidewise out of mesh with the gear 39 against the tension of the spring 51, by means of a shift rod 52. The shift rod 52 is provided with a head 53, engaged by a cam 54, formed on a lever 55, pivotally mounted on the shaft 12. This lever has a finger-piece 56, so that it may be rotated forwardly to cam the shift rod 52 toward the left and disengage the gear 40 from the gear 39. A depression 57 is provided in the cam lever 54, 55 to engage the head 53 at the end of the stroke of the lever, whereby the lever is prevented from accidental return.

Utility of the device will be readily understood when taken in connection with the above description. The tally-strip and work-sheet with the carbon-sheet between are properly adjusted on the platen 1. After a line is written the lever 7 is operated to give the desired line-space advance movement to the work-sheet. Through the connected gearing, the reel 38 will be turned at the same time an amount, however, preferably less than the line-space movement of the work-sheet. As the tally-strip 8 is drawn on, it unwinds from the roll of paper 9, thereby turning the gears 20, 21 and thus winding up the spring 32 until a given maximum tension thereof is obtained. Any further tendency to wind will merely cause a slipping between the gear 21 and the clutch formed on the hub 22. This will furnish a drag on the tally-strip 8 preventing the platen 1 and the work-sheet from advancing the tally-strip by friction an amount greater than that which the reel 38 provides for. If the tally-strip 8 should be advanced around the platen 1, a greater distance than desired, as in suddenly removing the work-sheet from the platen, preparatory to putting a new work-sheet on the platen, then the spring 32 and the friction clutch 21, 22 and 23 will yield preventing either the work-sheet or the tally-strip from being torn. When the excessive pull on the tally-strip 8 has ceased, the spring 32 will then rewind the paper roll 9 in a reverse direction, taking up the slack accidentally unwound.

Variations may be resorted to within the scope of the invention, and portions of the improvements may be used without others.

Having thus described my invention, I claim:

1. In a typewriting machine, the combi-

nation with a revoluble platen, of a tally-strip delivery spool from which a strip is led around the platen, means to engage the side margins of a work-sheet wider than the tally-strip, to press the work-sheet against the platen to travel therewith and permit relative travel between the work-sheet and the tally-strip, means for simultaneously line-feeding the platen and the tally-strip but at a substantially greater speed for the platen and work-sheet than for the tally-strip, whereby both the work-sheet and the platen tend by friction to advance the tally-strip unduly, and spring means for automatically retracting the tally-strip after the latter is unduly advanced.

2. In a typewriting machine, the combination with a revoluble platen, of a tally-strip delivery spool from which a strip is led around the platen, means to engage the side margins of a work-sheet wider than the tally-strip, to press the work-sheet against the platen to travel therewith and permit relative travel between the work-sheet and the tally-strip, means for simultaneously line-feeding the platen and the tally-strip but at a substantially greater speed for the platen and work-sheet than for the tally-strip, whereby both the work-sheet and the platen tend by friction to advance the tally-strip unduly, spring means for automatically retracting the tally-strip after the latter is unduly advanced, and a slip connection for limiting the degree of spring drag on the tally-strip.

3. The combination with a platen for holding a work-sheet and a tally-strip, of means for feeding said work-sheet by rotating said platen, separate advancing means for said tally-strip, a connected drive for said platen and said advancing means, means for disconnecting the advancing means of the tally-strip to permit independent driving of the platen, and a lock for preventing accidental operation of the disconnected advancing means.

4. The combination with a platen adapted to support a tally-strip, of unwinding means for drawing said tally-strip from a roll around said platen, a spring, means for supporting said roll, and a driving connection enabling said roll and its supporting means to wind up said spring as the tally-strip unwinds, so as to maintain the tension on said tally-strip.

5. The combination with a platen adapted to support a tally-strip, of unwinding means for drawing said tally-strip from a roll around said platen, a spring, means for supporting said roll, and a driving connection enabling said roll and its supporting means to wind up said spring as the tally-strip unwinds, so as to maintain the tension on said tally-strip, said driving connection

including a slip clutch acting to prevent an overwinding of said spring.

6. The combination with a platen adapted to support a tally-strip, of unwinding means for drawing said tally-strip from a roll around said platen, a pair of spool heads engaging said roll forming a spool thereof, a spring, and a train of gearing from one of said heads to said spring enabling said 10 roll and spool to wind up said spring so that said spring can maintain a drag on said tally-strip.

7. The combination with a platen for supporting a tally-strip, of unwinding means 15 for drawing said tally-strip from a roll around said platen, supporting means for said roll, a shaft, a spring fixed to one end of said shaft and fixed at the other end relatively to said shaft, and a train of gearing 20 having a slip connection to said shaft and connected to said roll, so as to enable said roll as it unwinds to put a limited tension on said spring, which will act back on said tally-strip.

8. The combination with a platen supporting a tally-strip, of unwinding means for drawing a tally-strip from a roll of the same around the platen, a shaft, a spring connected at one end to said shaft, and 30 fixed at the other end relatively to said shaft, a hub fixed to said shaft, a disk on

said hub, a gear mounted between said hub and said disk, spring means for maintaining frictional connection between said gear and both said hub and said disk, and a 35 second gear connected to said roll meshing with said first gear, so as to enable said roll to put a tension on said spring as the tally-strip is unwound, whereby said spring will maintain said tally-strip taut on said platen. 40

9. The combination of a revoluble platen, a shaft, a tally-strip delivery spool detachably connected to said shaft, a spring, and means whereby said shaft when driven by said spool may tension said spring, said tensioning means including a slip connection between the shaft and the spring, to determine the maximum tension of the spring. 45

10. The combination of a revoluble platen, a shaft, a tally-strip delivery spool detachably connected to said shaft, a second shaft, a spring which may be tensioned by means of said second shaft, and means, including a slip connection, for enabling the spool shaft to turn the spring shaft to tension the spring 50 to a point determined by said slip connection. 55
